UNITED STATES PATENT OFFICE

ALBERT E. HARRIS, OF SAN MARINO, CALIFORNIA, ASSIGNOR TO THOMPSON MANUFACTURING COMPANY, OF LOS ANGELES, CALIFORNIA, A CORPORATION OF CALIFORNIA

INTERMITTENT-MOTION ROTARY SPRINKLER

Application filed October 21, 1929. Serial No. 401,023.

This invention relates to a sprinkler device having a rotary head equipped with nozzles through which fluid is directed to a desired area of application.

5 This invention is an improvement on the sprinklers of the character disclosed in the U. S. patent to Guadalupe Buelna, No. 1,640,751, patented August 30, 1927, in which a sprinkler head is intermittently rotated as a result of reciprocation of a piston within a chamber. In this sprinkler the piston is moved in one direction by a spring and in the opposite direction by the accumulation 10 of water in the chamber. A valve situated 15 within the chamber is employed to alternately close and open an outlet and is retained respectively in closed and open positions by spring fingers which frictionally engage a lug formed on the valve member. The piston carries 20 a pair of springs adapted to apply opposing forces against the valve member, so that as the piston moves in one direction one of the springs will be compressed until the force exerted thereby against the valve member will 25 overcome the resistance of the spring fingers and allow the valve to snap over.

It is an object of my invention to provide in a valve mechanism of the character above described a slide member which will be moved through part of its movement as a result of positive pressure applied by a movable member, which may be a diaphragm or piston, and which slide member is moved through the remainder or final portion of its 30 stroke by a separate means which may be in the form of a collapsible toggle of the character hereinafter disclosed.

It is a further object of the invention to provide a valve mechanism of the above character which will open and close at predetermined positions of a pressure responsive member and which avoids the counterbalancing of a spring under compression against a frictionally engaging stop means.

45 A further object of the invention is to provide in the motivating mechanism for intermittently advancing a sprinkler head a flexible diaphragm adapted to be moved by the accumulation of fluid within a chamber.

50 A further object of the invention is to pro-

vide a motivating means for producing rotation of a sprinkler head having parts cooperating in such a manner that the sprinkler head will be intermittently pulled forwardly.

A further object of the invention is to provide a rotating sprinkler device with means for interrupting the flow of fluid through the nozzles thereof during a predetermined arc or portion of the revolution 55 of the sprinkler head, thereby making it possible to sprinkle one portion of a circular area without applying water to another portion of the circular area.

Further objects and advantages of the invention may be perceived from the following 60 part of the specification and the accompanying drawings, in which:

Fig. 1 is a partly sectioned elevational view 65 of a sprinkler device embodying the features of the invention, this view showing the valve in closed position.

Fig. 2 is a fragmentary view corresponding 70 to Fig. 1 and showing the motivating mechanism at the end of a reciprocation whereby an intermittent movement of the 75 sprinkler head or distributor has been accomplished.

Fig. 3 is a fragmentary vertical section 80 showing the valve operating mechanism in raised position and the valve of the device in closed position.

Fig. 4 is a sectional view similar to Fig. 3 showing the valve operating mechanism in an intermediate position.

Fig. 5 is a fragmentary vertical cross section 85 on a plane represented by the line 5—5 of Fig. 1.

Fig. 6 is a horizontal cross section on planes 90 represented by the line 6—6 of Fig. 2.

Fig. 7 is a horizontal cross section on a plane represented by the line 7—7 of Fig. 2.

Fig. 8 is a fragmentary perspective view 95 for illustrating the operation of the pawl and lever mechanism of the invention to pull the distributor or sprinkler head of the sprinkler device in forward rotative direction.

The preferred form of my invention, as shown in Figs. 1 and 2, has a delivery mem- 100

ber 11 which consists of a fitting 12 adapted to be threaded on the end of a pipe 13, and a tubular arbor or barrel 14 which threads into and projects upwardly from the fitting 12, the upper end of the hollow arbor 14 having a flange 15 on the upper end thereof whereby a radial annular shoulder 16 is formed. For purpose of engagement by a tool to screw the arbor 14 into the fitting 12, a diametral slot 17 may be milled in the upper end thereof. On the delivery member 11 a rotatable distributor member 20 is mounted, this distributor member including a tubular wall structure 21 fitting the arbor 14 between the shoulder 16 and the upper extremity 22 of the fitting 12, an enlargement 23 at the upper end of the tubular wall structure 21, a nozzle head 24 which makes threaded engagement at 25 with the enlargement 23, and a cylindrical wall 26 having a valve cap 27 at the upper end thereof and a flexible diaphragm 28 secured in the lower end thereof by means of a fitting 29 which is held in place by a threaded ring 30, a chamber 31 being thereby formed within the cylindrical wall 26.

Within the cylindrical bore 32 of the nozzle head 24 which forms part of the distributor member 20, a tubular valve member 33 may be placed, this tubular valve member being of such external diameter that it will closely fit the bore 32 and having downwardly projecting lugs 34 which extend into the ends of the slot 17 in the upper end of the arbor 14, this interengagement of the lugs 34 with the arbor 14 preventing rotation of the tubular valve member 33 as the distributor 20 is rotated relative thereto.

To permit a flow of water, or other fluid, from the interior of the arbor 14 into the annular passage 36 of the enlargement 23, the lower edge 37 of the tubular member 33 may be relieved, as indicated in Fig. 2, or the lower portion of the member 33 may be perforated in alignment with the annular passage 36, as may be desired. The upper, diametrically enlarged portion 38 of the member 33 has an aperture 40 therein, aligned with the inner ends 41 of water passages 42 in the extending arms 43 of the nozzle head 24, these arms 43 having nozzles 44 of a desired character threaded in the ends thereof, as indicated at 45. As the distributor 20 rotates, the inner ends 41 of the passages 42 will alternately traverse the aperture 40 in the tubular member 33 so that during such portions of the rotary movement of said passages 42, water will pass therethrough to be discharged through the nozzles 44. As the inner end 41 of each passage 42 traverses the parti-cylindrical wall portion 46 circumferentially adjacent to the aperture 40, it will be closed off by such wall portion 46, and the flow of water therethrough will be interrupted. It will be readily perceived that by proportioning the

arcuate lengths of the aperture 40 and the wall 46, any desired angular area forming a part of the complete circular area which the sprinkler device is capable of sprinkling may alone be sprinkled and the remaining portion of the circular area left unsprinkled.

For instance, the sprinkler may be placed at the corner of a rectangular area to be sprinkled, and the arc of the aperture 40 may be made 90°, with the result that as each of the passages 42 rotates, it will traverse the aperture only during its passage through an angle of 90° coincident with the angle of the corner at which the sprinkler is placed, thereby causing the sprinkling of the sector within the corner of the previously mentioned area without sprinkling outside of this area. The valve member 33 may be readily removed so that the nozzles 44 will sprinkle a complete circular area.

In the upper end of the valve cap 27 is an outlet passage 47 for egress of water from the chamber 31. Aligned with the inner end of the outlet 47 is a guide tube 50 which is threaded at 51 into a counterbore formed in the lower face of the cap 27. The guide sleeve 50 holds a U-shaped spring member 52 in such position that the arms 53 of the spring member 52 will project downwardly within the chamber 31. Carried in the guide sleeve 50 is a valve member 55, the upper end 56 of which is diametrically reduced and is prepared with a cone point for closing the outlet 47. As shown in Fig. 5, the valve member 55 is equipped with an outwardly extending pin 58, this pin projecting through a vertical slot 59 in the guide sleeve 50 and through a vertical slot 60 in a slide member 61 which is adapted to slide vertically on the guide sleeve 50.

The slide member 61 has a square body portion 62 formed intermediate its ends, which body portion is drilled on opposite sides to receive the ends 63 of toggle arms 64 and 65, these toggle arms 64 and 65 making pivotal engagement at 66 and 67 with the lower ends of the spring arms 53.

The diaphragm 28 is preferably made of molded rubber and by means of a screw 68 secured therein holds a yoke 69, which, as shown in Fig. 3, includes upwardly extending fingers 70 adapted to engage the upper face of a flange 71 formed at the lower end of the tubular portion 72 of the slide member 61. When the water in the water distributing system is turned off so that there is no pressure exerted within the distributor 23, the diaphragm 28 will be forced into raised position, as shown in Fig. 1, by a vertically reciprocating member 73 which slides vertically in the bore of a tubular wall 74 which projects upwardly from the lower end of the fitting 29, there being a spring 75 which engages the lower face of a head 76 on the upper end of

the member 73, thereby holding the head 76 in engagement with the lower central surface of the diaphragm 28 and constantly urging the diaphragm upwardly. When the diaphragm 28 is in the raised position shown in Fig. 1, the surface 77 of the yoke 69 will rest against the lower end of the guide sleeve 50.

When the distributing system to which the sprinkler is attached is turned on, water under pressure will flow upwardly through the arbor 14, and a portion thereof will pass through the annular passage 36 of the enlargement 23, through a radial recess 80 communicating with the annular passage 36, and through a passage 81 which is controlled by a flow regulating valve 82, into the chamber 31. As water accumulates in the chamber 31 due to the valve member 55 closing the outlet 47, the diaphragm 28 will be forced downwardly from the position in which it is shown in Fig. 1 to such position that the fingers 70 of the yoke 69 will approach the flange 71 of the slide member 61, as shown in Fig. 3, and as the downward movement of the diaphragm 28 continues, the fingers 70 of the yoke 69 will move the slide member 61 downwardly toward and through the intermediate position shown in Fig. 4, the toggle arms 64 and 65 swinging from diagonal and crossing positions, such as shown in Fig. 3, toward substantially horizontal positions, as indicated in Fig. 4, the spring arms 53 being flexed outwardly from their positions of Fig. 3 to their positions of Fig. 4 due to the expansion of the toggle device formed by the toggle arms 64 and 65.

Then, as the downward movement of the slide member 61 is continued, the toggle arms 64 and 65 will be swung further downwardly toward a position indicated by the dotted lines 83 of Fig. 4, at which time the resilient collapsing force exerted by the spring arms 53 will cause a collapsation of the toggle device, due to the downward component of the diagonal forces exerted on the slide member 61 through the toggle arms 64 and 65, and will thereby produce an abrupt downward movement of the slide member 61 to the position thereof indicated in Fig. 2. During this downward movement under resilient force exerted by the toggle device, the upper end wall 84 of the slot 60 in the slide member 61 will engage the pin 58 of the valve member 55 so as to pull the valve member downwardly from its closed position of Fig. 1 to its open position of Fig. 2. It will be perceived that the downward movement of the slide member 61 consists of two portions: first, an initial downward movement which is accomplished by engagement of the fingers 70 with the flange 71, and second, a final downward movement which is produced by a separate means such as the toggle arms 64 and 65 which are normally urged toward upper and lower col-

lapsed positions, such as indicated in Figs. 3 and 2, by the spring arms 53.

During the initial portion of the downward movement of the slide member 61, the slot 60 moves relative to the pin 58, but during the final portion of the downward movement, the end 84 of the slot 60 engages and moves the pin 58 downwardly and produces the withdrawal of the valve member 55 from a closing position relative to the outlet 47, whereupon the water impounded in the chamber 31 will discharge through openings 49 in the member 50 and the outlet 47, thus permitting the diaphragm 28 to be moved upwardly from its position of Fig. 2 toward its position of Fig. 1. As the yoke 69 is moved upwardly by the diaphragm 28, the face 77 thereof forces the slide member 61 upwardly from its position of Fig. 2 toward and to its position of Fig. 4. This upward movement of the slide member 61 by the yoke 69 which forms part of a movable member actuated in one direction by fluid within the chamber 31 may be termed the initial upward or closing movement of the slide member, and during such initial closing movement of the slide member the slot 60 may move relative to the pin 58, or the lower end 85 of the slot 60 may, during this upward movement, engage and start to move the pin 58 upwardly. When the slide member 61 approaches or assumes the position indicated in Fig. 4, the toggle arms 64 and 65 will have swung into such upwardly sloping position that the spring arms 53 will cause collapsation of the toggle device and subsequent movement of the toggle arms 64 and 65 and the slide member 61 into the positions in which they are shown in Fig. 3, the flange 71 at the lower end of the slide member 61 being raised from engagement with the surface 77 of the yoke 69 into a position adjacent to the upper ends of the fingers 70.

The movement of the slide member 61 upwardly by the toggle device from the position in which it is shown in Fig. 4 to the position in which it is shown in Fig. 3 constitutes the final upward or closing movement of the slide member 61, and it is during and at the end of this final closing movement of the slide member 61 that the valve member 55 is carried into closed position, as indicated in Fig. 3.

The closing of the opening 47 immediately stops the egress of water from the chamber 31, with the result that the influx of water through the inlet passage 82 will immediately start a downward movement of the diaphragm and initiate a second cycle of operation of the motivating mechanism of the sprinkler. It will be seen that the movement of the diaphragm does not actually open or close the valve 55 but merely imparts an initial movement to the slide member 61 so that the slide member may then be moved through a final, valve operating movement by the sep-

arate means embodied in the toggle device represented by the toggle arms 64 and 65.

The member 73 is bifurcated at its lower end 90 and by use of a pin 91 pivotally engages the end of the primary portion 89 of a lever 92 which is preferably made in the form of a bell crank and is intermediately pivoted on a pin 93 carried in the lower end of a bar 94 secured by screws 95 to the fitting 29 and extending downwardly therefrom, as shown in Fig. 2.

The secondary portion 96 of the lever or bell crank 92 has a pulling pawl 97 pivoted thereto at 98, the outer end of the pawl 97 being enlarged to form a weight 99 and having a downwardly projecting tooth 100 adapted to engage teeth 101 of a circular ratchet 102 formed concentrically on the fitting 12 of the delivery member 11.

In Fig. 8 the member 73 is shown in raised position to correspond to Fig. 1. As the diaphragm 28 is moved downwardly under pressure and due to the accumulation of water in the chamber 31, the member 73 will be forced downwardly against the lifting action of the spring 75, and the bell crank lever 92 will be swung into the position in which it is shown by dotted lines 105 in Fig. 8, with the result that a pulling action will be exerted on the ratchet 102 by the tooth 100 of the pawl 97, and the distributor will be thereby pulled forwardly through a small arc of rotation. When the valve 55 is opened in the manner previously described and the member 73 is allowed to move upwardly under the impelling forces of the spring 75, the bell crank lever 92 will be returned from its final position shown in Fig. 2 to its initial position shown in Figs. 1 and 8, the pawl 97 being moved over into a new position of engagement with the ratchet 102 and ready for a subsequent distributor advancing operation.

The control valve 82, shown best in Fig. 6, may have a slotted end 110 projecting into the passage 81, and thereby the flow of water into the chamber 31 may be controlled and varied to produce a desired timing of the intermittent advancing operation of the motivating mechanism hereinbefore described.

I have herein shown a simple and practical form of my invention, but it is recognized that certain parts or elements thereof are representative of other parts, elements, or mechanisms which may be employed in substantially the same manner to accomplish substantially the same results; therefore, it is to be understood that the invention shall not be limited to the details disclosed herein but shall have the scope set forth in the following claims.

I claim as my invention:

1. A sprinkler of the character described having a delivery member and a distributor, including: walls forming a chamber adapted to receive fluid from said delivery member,

an inlet for ingress of a controlled flow of fluid into said chamber, and an outlet for egress of fluid from said chamber; a valve for closing said outlet; a slide member having initial and final closing movements and initial and final opening movements; a spring collapsed toggle device for moving said slide member through its respective final movements after it has been moved through its respective initial movements; a movable member moved by accumulation of fluid in said chamber when said outlet is closed, said movable member having parts engaging said slide member so as to move said slide member through its respective initial movements; parts carried by said slide member for respectively closing and opening said valve during the respective final closing and opening movements of said slide member; and means operated in consequence of the movement of said movable member to move said distributor relative to said delivery member.

2. A sprinkler of the character described having a delivery member and a distributor rotatively movable relative to said delivery member, including: walls forming a chamber adapted to receive fluid from said delivery member, an inlet for ingress of a controlled flow of fluid into said chamber, and an outlet for egress of fluid from said chamber; a valve for closing said outlet; a slide member having initial and final closing movements and initial and final opening movements; a spring collapsed toggle device for moving said slide member through its respective final movements after it has been moved through its respective initial movements; a movable member moved by accumulation of fluid in said chamber when said outlet is closed, said movable member having parts engaging said slide member so as to move said slide member through its respective initial movements; parts carried by said slide member for respectively closing and opening said valve during the respective final closing and opening movements of said slide member; and means operated by said movable member for intermittently moving said distributor forwardly.

3. A sprinkler of the character described having a delivery member and a distributor rotatively movable relative to said delivery member, including: walls forming a chamber adapted to receive fluid from said delivery member, an inlet for ingress of a controlled flow of fluid into said chamber, and an outlet for egress of fluid from said chamber; a valve for closing said outlet; a slide member having initial and final closing movements and initial and final opening movements; a spring collapsed toggle device for moving said slide member through its respective final movements after it has been moved through its respective initial movements; a movable member moved by accumulation of fluid in said chamber when said

- outlet is closed, said movable member having parts engaging said slide member so as to move said slide member through its respective initial movements; parts carried by said 5 slide member for respectively closing and opening said valve during the respective final closing and opening movements of said slide member; a ratchet; a lever reciprocated by said movable member; and a pawl carried by 10 said lever, said pawl engaging said ratchet whereby to intermittently move said distributor.
4. A sprinkler of the character described having a delivery member and a distributor 15 movably mounted relative to said delivery member, including: walls forming a chamber adapted to receive liquid from said delivery member, an inlet into said chamber for ingress of liquid under pressure and an 20 outlet for egress of liquid from said chamber; a movable member moved relatively outwardly by accumulation of fluid in said chamber; a valve controlling the flow through said outlet; a slide member moved 25 by said movable member and engaging and closing said valve near the end of its closing stroke and engaging and opening said valve near the end of its opening stroke; a spring collapsed toggle member engaging said slide 30 member in a manner to resiliently force said slide member toward the extremes of the positions of said slide member; and means operating in consequence of the movement of said movable member to move said distributor. 35
5. A sprinkler of the character described having a delivery member and a distributor, including: walls forming a chamber adapted to receive fluid from said delivery member, 40 an inlet for ingress of a controlled flow of fluid into said chamber, and an outlet for egress of fluid from said chamber; a valve for closing said outlet; a slide member having initial and final closing movements and 45 initial and final opening movements; a collapsible toggle mechanism for moving said slide member through its respective final movements after it has been moved through its respective initial movements; pressure 50 transferring means moved by the accumulation of fluid in said chamber when said outlet is closed and engaging said slide member so as to move said slide member through its respective initial movements; parts carried by 55 said slide member for respectively closing and opening said valve during the respective final closing and opening movements of said slide member; and means operable in consequence of the movement of said pressure 60 transferring means for moving said distributor relative to said delivery member.
6. A sprinkler of the character described having a delivery member and a distributor, including: walls forming a chamber adapted 65 to receive fluid from said delivery member,
- an inlet for ingress of a controlled flow of fluid into said chamber, and an outlet for egress of fluid from said chamber; a valve for closing said outlet; a slide member having initial and final closing movements and 70 initial and final opening movements; a collapsible toggle mechanism for moving said slide member through its respective final movements after it has been moved through its respective initial movements; pressure 75 transferring means comprising a diaphragm moved by the accumulation of fluid in said chamber when said outlet is closed and engaging said slide member so as to move said slide member through its respective initial movements; parts carried by 80 said slide member for respectively closing and opening said valve during the respective final closing and opening movements of said slide member; and means operable in consequence of the movement of said pressure transferring means for moving said distributor relative to said delivery member.
7. A sprinkler of the character described having a delivery member and a distributor, 85 including: walls forming a chamber adapted to receive fluid from said delivery member, an inlet for ingress of a controlled flow of fluid into said chamber, and an outlet for egress of fluid from said chamber; a valve for closing said outlet; a slide member having initial and final closing movements and 90 initial and final opening movements; a collapsible toggle mechanism for moving said slide member through its respective final movements after it has been moved through its respective initial movements; a diaphragm member moved by the accumulation of fluid in said chamber when said outlet is closed and engaging said slide member so as to move said slide member through its respective initial movements; parts carried by 95 said slide member for respectively closing and opening said valve during the respective final closing and opening movements of said slide member; and means operable in consequence of the movement of said diaphragm member for moving said distributor relative to said delivery member.
- In testimony whereof, I have hereunto set 100 my hand at Los Angeles, California, this 5th day of October, 1929.
- ALBERT E. HARRIS.
